GALVANOMETER RELAY

Archie J. McMaster, Highland Park, and Walter Van Guilder, Oak Park, Ill., assignors to G-M Laboratories, Inc., Chicago, Ill., a corporation of Illinois

Application September 5, 1936, Serial No. 99,672

22 Claims. (Cl. 200—56)

The present invention relates generally to electric relays and more particularly to relays which are highly sensitive in that they require only very small amounts of power for controlling them.

The relay of the present invention comprises a taut suspension D'Arsonval galvanometer movement and a clamping and contact operating mechanism adapted to clamp a pointer carried by the galvanometer coil. The galvanometer movement, in response to the control current in its coil moves its pointer into or out of the position in which it may be engaged by the clamping jaws or bars, and the clamping mechanism 10 periodically attempts to clamp the pointer. Contacts are operated each time that the pointer is caught between the clamping jaws.

The relay of the present invention employs a plurality of independent contacts operated by 20 separate clamping jaws or bars which are disposed at various positions along the arc of travel of the galvanometer pointer. It includes also mechanisms for conveniently moving or adjusting the clamping jaws along the path of travel 25 of the galvanometer pointer so as to vary the values of control current at which the pointer encounters or escapes particular clamping jaws. The adjusting mechanism is arranged to prevent any adjustment of the jaws while they are in a 30 clamping attitude with respect to the pointer.

The invention further provides means for indicating visually on a graduated scale both the deflection of the galvanometer needle and the adjusted position of the clamping members.

The present invention further provides new and novel mechanisms for providing the operations and functions mentioned and described above.

It is an object of the present invention to provide an improved relay of the type indicated, which is rugged and reliable and otherwise suitable for use in industrial control apparatus.

It is a further object of the present invention to provide improved apparatus for performing the 45 above described functions.

These and other objects and advantages of the present invention will become apparent as the description proceeds.

The following description of a specific embodiment of the present invention, when taken in connection with the accompanying drawings will enable those skilled in the art readily to understand the invention and to practice the same. In the drawings:

55 Fig. 1 is a general view in perspective of the

exterior of a relay embodying the present invention;

Fig. 2 is a general view in perspective of the internal mechanism of the device illustrated in Fig. 1;

Fig. 3 is an exploded view showing some of the pieces and partial assemblies of the apparatus of Figure 2 individually in perspective;

Figs. 4 and 5 are horizontal and vertical sections respectively of the device of Fig. 1, Fig. 4 being a section taken along the line 4—4 of Fig. 5, and Fig. 5 being a section taken along the line 5—5 of Fig. 4;

Fig. 6 is an elevation partly in section taken along the line 6—6 of Fig. 5;

Fig. 7 is a section taken along the line 7—7 of Fig. 5;

Fig. 8 is a section taken along the line 8—8 of Fig. 6;

Fig. 9 is a partial view showing the apparatus of Fig. 4 in a different operated position; and,

Fig. 10 is an enlarged sectional detail taken along the line 10—10 of Fig. 4.

The apparatus illustrated in Fig. 2 includes a D'Arsonval galvanometer and a contact making mechanism controlled by the galvanometer. The galvanometer itself comprises a die-casting 10 of non-magnetic material such as a zinc alloy. (See Figs. 3, 4 and 5.) The die casting 10 serves as a housing as well as a supporting frame for a portion of the galvanometer apparatus. A pair of iron pole pieces 11 and 12 (Fig. 3) are imbedded in the die-casting 10 and each pole piece extends from the exterior of the casting or housing 10 entirely through the wall thereof into the interior cavity thereof. Preferably, the pole pieces 11 and 12 are placed in the mold at the time the die-casting 10 is struck so that the casting is formed about the pole pieces 11 and 12. The pole pieces conveniently may have irregular surfaces such as indentations 14 shown in the section of Fig. 8 into which the metal of the die casting may flow for securely locking the pole pieces in position.

Supported on a boss 16 of the die-casting 10 (Fig. 5) is a core 15 positioned between the two interior faces of the pole pieces 11 and 12 so as to provide two air gaps as shown in Figs. 3 and 8. Like the pole pieces 11 and 12, the core 15 is of iron or similar magnetic material. A magnet 26 (Figs. 2 and 5) completes the magnetic circuit and provides the magnetic flux in the two gaps already mentioned.

A coil 17 is supported on two taut suspension wires 18 and 19 which in turn are supported on 55

resilient metal tabs 21 and 22 (Figs. 3 and 5). These tabs 21 and 22 in turn are supported on insulating disks 23 and 24 which are directly supported by the die-casting 10. The loop 5 shaped coil 17 has one of its sides lying in each of the air gaps provided between the core 15 and the pole pieces 11 and 12. A pair of non-magnetic plates 27 and 28 (Figs. 3, 5 and 8) are placed over the core 15 and cover the two magnetic gaps near the tips of the pole pieces 11 and 12 so as to confine and protect the coil 17.

The two suspension wires 18 and 19 consist of very fine gold ribbon or the like, and they are held taut by the resilient tabs 21 and 22. The 15 resilient tabs 21 and 22 support these ribbon suspensions 18 and 19 at the center of the disks 23 and 24 so that the axis of rotation of the coil 17 coincides with the centers of the disks 23 and 24. The suspension wires 18 and 19 not only support 20 the coil 17 mechanically but they also serve as the electrical connections thereto, the adjacent ends of the wires 18 and 19 being connected to the winding of the coil 17 for this purpose. The torsion of these wires provides the restoring force 25 of the coil. Each of the two insulating disks 23 and 24 is rotatably adjustable in the casting 10 for setting and adjusting the rest or zero position of the coil 17.

As best may be seen in Figs. 3 and 7, the upper 30 disk 23 is notched and this notch is adapted to engage an internal projection 31 of a rotatable cap 32. This cap 32 fits onto the die-casting 10 and rotates thereon about an axis substantially concentric with the center of the disk 23. The 35 projection 31 of the cap is adapted to engage shoulder faces 32 of the casting 10 so as to limit the angle through which the disk 23 may be rotated. The cap 32 is adapted to be rotated manually by the users of the instrument so as to 40 permit manual rotation of disc 23 for correcting the zero position of the coil 17. The limited angle of rotation prevents the user from carelessly or accidentally rotating the disc 23 continuously in one direction to thereby damage the 45 suspension wire 18 by twisting it excessively. The disk 24 also rotates in the casting 10. This disk is not provided with any stops for limiting its rotation because it is not accessible for adjustment unless the device is partially dismantled. It is intended to be used only as a factory 50 adjustment.

Secured to the top of the coil 17 is a piece of formed non-magnetic wire 35 (see Fig. 5). One end of this wire extends upwards substantially parallel to, alongside and in front of the upper suspension wire 18 and bends forward at a right angle for receiving a pointer 36, which consists of a thin-wall aluminum tube. This tube carries a small fiber bushing 37 near the outer 55 end thereof to protect it and prevent it from collapsing under the mechanical force of the clamping mechanism to be described presently. The extreme end of the pointer 36 is collapsed for bending it and also for providing a blade like portion 38 for cooperating with a visual scale 39. (See Figs. 2, 3 and 5). The other end of the wire 35 (see Fig. 5) extends back from the coil 17 at right angles to the suspension wire 18, that is, in a direction opposite to that of the 60 pointer 36 and its bushing 37. It extends through an aperture in the main galvanometer die-casting 10 and carries at its end a counter-weight 41 for balancing the weight of the pointer 36 and its bushing 37. A box-like cover 42 closes 65 this aperture and gives the counter-weight 41

room to swing from side to side within the enclosure as the coil 17 rotates.

A pair of terminal screws 43 and 44 (Fig. 5) are secured to the casting 10 with insulating washers. These terminal screws are connected to the spring tabs 21 and 22 to provide electrical connections to the coil 17 of the galvanometer. The wire 45 connecting the terminal 23 to the upper tab 21 extends from the tab 21 down through the hole in the disk 23, then down along 10 the interior wall of the casting 10, passing between the wall of the casting 10 and the guard plate 28 at one side of the boss 16, all to avoid touching the suspension 18, the coil 17, or the wire 35 which carries the counterweight 41. 15

A galvanometer front plate 46 (Figs. 5, 6 and 7) fits over the die-casting 10 so as to close entirely the bottom and front thereof except for an opening at the front near the top where the pointer 36 emerges. The plate 46 includes a tab 20 or tail 47 which hooks under the U portion of the magnet 26 for supporting the weight thereof and for holding the magnet in position on the pole pieces 11 and 12. The plate 46 also includes lateral projections 48, 49, 50 and 51 which support the magnet at the front. A bar 53 secured to the back of the die-casting 10 supports the magnet at the back and clamps it against the projections 48, 49, 50 and 51. 25

The front plate 46 also supports an electric 30 motor 55 (see Figs. 2 and 5) and a bell crank 57, (see Figs. 3, 5 and 6) which constitute a part of the clamping and contact operating equipment. The electric motor 55 preferably is of a type which operates on alternating current and 35 employs shading coils for obtaining a magnetic phase displacement which in turn produces the effect of a rotating magnetic field for turning the rotor. The motor includes coils 60, a magnetic field structure 61, shading coils 62, and an enclosed rotor structure 63. The rotor structure 63 includes a reduction gear (not illustrated in detail). The single shaft 64 extending from the reduction gear turns at a slow speed, such as, for example, a speed of one revolution per minute. 40 The shaft 64 carries a cam 65 which operates the bell crank 57. Thus the motor lifts the clamping mechanism through the bell crank 57 once each minute. 45

Referring particularly to Fig. 2, the clamping 50 mechanism includes a pair of clamp bars 71 and 72 which are adapted to be raised periodically by the electric motor 55. These clamp bars are 55 arcuate in contour and lie under the path of travel of the bushing 37 on the pointer 36. Above the bushing 37 is an arcuate stationary bar 73 against which the bushing 37 is adapted to be pressed by the bars 71 and 72. The galvanometer structure including the pointer 36 as well as the resilient tabs 21 and 22 which support 60 the taut suspension wires 18 and 19 (see Fig. 5) are sufficiently resilient to permit the pointer 36 to be moved this slight distance to be brought into engagement with the bar 73. Quite obviously, the bushing 37 normally must lie a small 65 distance removed from the upper, or stationary, bar 73 because it can not be permitted to touch the bar 73 at the time that it is required to move under force of the current in the coil 17 or under the restoring force of the suspension wires 18 70 and 19. 75

The separate clamp bars 71 and 72 have separate contacts 74 and 75 associated with them which they are adapted to operate. A clamp bar operates its contacts only when it catches the

pointer between it and the bar 73 as it is raised by the motor 55. The arcuate clamp bars 71 and 72 are separated by a slight gap sufficient to receive the bushing 37 and thereby permit the pointer 36 and its bushing 37 simultaneously to escape both bars. The two clamp bars 71 and 72 are adapted to be rotated about the axis of rotation of the pointer 36 so as to permit the gap between the arcuate clamp portions 71 and 72 to be set at any position along the path of travel of the bushing 37 carried by the pointer 36. If the pointer occupies a position at either side of this gap at the time the clamp bars 71 and 72 are raised by the motor 55, it will be caught by one of the bars so as to cause that clamp bar to operate its contacts.

The construction of the individual parts of the clamping and contact making mechanism may be seen best in the exploded view of Figure 3.

20 Referring to Figs. 3, 4 and 5, a ring shaped rocker 76 is pivoted, by means of pins which are fastened in the rocker 76, to the die-casting 10 at 77 and 78 where the casting is given extra section for that purpose. These two pins which carry 25 the rocker 76 lie on an axis which is substantially perpendicular to the axis about which the coil 17 rotates and which also is substantially perpendicular to the pointer when the same is in its median position in its limited arc of motion. A 30 pair of arms depending from the rocker 76 at its forward side, and at a position removed from the axis of its support on the casting 10, carry a roller 79 which is engaged by one arm of a bell crank 57.

35 The bell crank 57 is journaled on the galvanometer front plate 46 at a position to one side of the roller 79 and off the axis of the slow speed shaft 64 of the motor 55. The cam 65 carried by the shaft 64 engages the bell crank 57 and 40 slowly oscillates it. The crank 57 in turn oscillates the rocker 76 by periodically lifting and lowering its forward side through the engagement with the roller 79. The weight of the clamping apparatus carried by the rocker 76 (to be described presently) provides a restoring force for 45 maintaining the roller 79 in engagement with the crank 57 and also for maintaining the crank in engagement with the cam 65. If desired, a spring may be added to the mechanism for increasing 50 this restoring force.

The rocker 76 includes on its periphery a circular seat for a ring 81 which is adapted to rotate thereon. The center about which the ring 81 rotates on the rocker 76 is substantially coincident with the center of rotation of the coil 17, that is, the position of the suspension wires 18 and 19, when the rocker 76 is in a level position. The ring 81 has teeth 82 (see Figs. 3 and 4) formed in its periphery so as to face approximately upward. These teeth are adapted to engage a screw or worm 114 located just above it at the rear portion of the ring 81 (see Figs. 4 and 5) so that the ring 81 may be rotated on the rocker 76 in a manner to be described more fully presently, 65 and so that the teeth 82 may disengage the worm 114 in a manner also to be described. The rocker 76 and the ring 81 are notched at their front portions to permit their being put in place on the die casting 10 or removed therefrom while the 70 pointer 36 of the galvanometer is in place thereby facilitating assembly. A pair of resilient clips 102, one of which is shown in each of the Figs. 3 and 4, are secured to the top of the rocker 76. They engage the upper surface of the ring 81 75 to hold it in assembled relation with the rocker

76 and frictionally to restrain rotation of the ring 81 on the rocker 76.

The ring 81 carries a pair of clamp frames 83 and 84 which are secured to projections 85 and 86 thereof by means of pins such as pin 87, the frames 83 and 84 being free to swing up and down about these pins through a considerable angle. These frames 83 and 84 include the arcuate clamp bars 71 and 72 already referred to. Extending under the clamp frames 83 and 84 are 10 contact structures which include the contacts 74 and 75 already referred to.

The details of the contact structure may be seen best in Fig. 10 which is an enlarged sectional view of the contact structure 74 associated with the clamp frame 83. A portion 89 of the ring extends out below and between the projections 85 and under the clamp frame 83. A sheet of fiber 91 somewhat wider than the portion 89 of the ring 81 is wrapped about the portion 89 and 20 the contact assembly is attached under it, the parts being added in the following order: Resilient contact blade 92, a terminal piece 93, an insulator 94, resilient contact blade 95, terminal piece 96 and a capping plate 97. A capping plate 25 98 similar to plate 97 is also placed over that portion of the fiber piece 91 which lies above the extension 89 of the ring 81. A pair of insulating bushings 101 extend through the entire assembly excepting only the two capping plates 97 and 98. 30 A pair of rivets 102 extend through the entire assembly for holding it together. The wide piece of fiber 91 extends beyond the several contact pieces and also beyond the piece 89 of the ring 81 for the purpose of providing the large electrical 35 clearances required in industrial apparatus for circuits of commercial voltages such as, for example, 230 volts. The structure just described supports the two resilient contact blades 92 and 95 on the ring 81 and insulates the ring 81 and 40 each of the separate contact blades 92 and 95 from each other. The blades 92 and 95 carry contact buttons at their ends which are adapted to engage each other so as to constitute the contacts 74 already mentioned.

The clamp-frame 83 being pivoted at 87 rests on the contact blade 92 so that its weight is supported thereby. The tension of the blade 92 must be sufficient to support firmly the frame 83; and the spring 92 must be adjusted to bring the 45 arcuate clamp bar 71 of the frame 83 slightly below bushing 37 on the pointer 36 when the entire contact assembly has been dropped to its low position by the motor 55. The blade 95 is adjusted so that its contact is spaced slightly from the contacts of the blade 92 and so that when the contact assembly is raised by the motor 55 and the bar 71 engages the bushing 37 on the pointer 36 and presses it against the bar 73, the contacts will be brought into engagement. A similar contact 50 assembly is associated with the clamp frame 84 and its arcuate clamp bar 72.

A cover 105 is secured to side extensions 106 and 107 of the main die casting 10, the cover 105 being provided with bosses 109 and 110 for that purpose (Fig. 4). The cover 105 is molded of a condensation product but may be die-cast of metal. The cover 105 has an aperture through which the cap 32 extends, and the cover 105 fits over a rim 111 of the cap 32 to retain it in place 55 atop the main die casting 10. The cover 105 has journaled therein a shaft 113 which carries the worm 114 engaging the teeth of the ring 81 as already described.

A resilient bowed washer 116 on the shaft 113 75

at one end of the worm 114 holds the shaft 113 in a fixed position axially so as to hold the ring 81 and the clamp bars 71 and 72 firmly in any position to which they may be adjusted. The end 5 thrust thus provided between the shaft 113 and its bearings serves frictionally to restrain rotation of the worm 114 so as to maintain its adjustment. The shaft 113 also carries a knob 115 outside of the cover 105 to permit the shaft and the 10 worm 114 to be rotated manually for adjusting the angular position of the ring 81 on the rocker 76 and for thereby adjusting the position of the clamp bars 71 and 72 along the path of travel of the pointer 36.

15 In the position in which the clamping and contact mechanism including the rocker 76, the ring 81 and contact bar 72 is shown in Fig. 5, the bar 72 is in its lowest position so as to avoid engaging the bushing 37 carried by the pointer 36, and the 20 teeth of the ring 81 engage the threads of the worm 114. While the apparatus is in this condition, the shaft 113 and the worm 114 may be rotated by means of the knob 115 so as to rotate the ring 81 in its seat on the rocker 76 and thereby to move 25 the gap which occurs between the two clamp bars 71 and 72 to a different position along the path of travel of the bushing 37. Fig. 9 illustrates the clamping and contacting mechanism in a slightly different operated position. In Fig. 9 the clamp 30 bar 71 has been raised by the motor 55 to the position in which it just initially touches the bushing 37 carried by the pointer 36. At this position of the rocker 76 and ring 81, the teeth of the ring 81 have moved down and away from the teeth of 35 the worm 114 so as to clear the same. In this connection it is to be observed that the axis of the pins 77 and 78 about which the rocker 76 tilts is forward of the worm 114, so that, as the clamp bars 71 and 72 are raised, the rear portion of the ring 81 drops to carry its teeth out of engagement and clear of the teeth of the worm 114. It 40 is desirable that the teeth of the ring 81 should entirely clear those of the worm 114 before either clamp bar touches the bushing 37 carried by the pointer 36 so as to prevent the clamp bars from being rotated manually when the apparatus is in such a condition that the needle 36 might be carried along with the clamp bars. In any event, these teeth should clear before the bushing 37 45 has been pressed against the stationary bar 73, since then any motion of the clamp bars would tend to roll the bushing 37 between the clamp bar 71 for example and the stationary bar 73, and rotate the needle 36 on the wire 35.

50 The cover 105 also carries the scale 39, which may be constructed of transparent cellulose material. The scale 39 includes a curved strip of transparent material having a series of ruled lines and numerical indexes 121 printed thereon to 55 provide the graduations and characters with respect to which the positions of the pointers 36 and 122 are to be read. (Pointer 122 will be described presently.) Preferably the characters 121 are printed on the inside or back surface 60 and are adapted to be viewed through the transparent material of the scale. The printed strip is then coated on its back or inside surface with an opaque material having a color contrasting 65 with that of the printed characters. The coating is omitted immediately above and below the graduations 121 so as to leave windows 119 and 120. The pointer 36 has its flat or blade portion 38 directly behind the upper window 120 through 70 which it may be viewed so that its position may 75

be noted visually with respect to the graduations of the scale.

The clamp frame 84 carries the pointer 122 extending from the front face of the arcuate clamp bar 72. This pointer is offset to bring it 5 into alignment with the gap between the arcuate clamp bars 71 and 72, and it terminates near the lower window 119 of the scale 39 through which it may be viewed for reading its position with respect to the scale. The portion of the pointer 10 122 which is visible through the window of the scale is aligned with (1) the center of rotation of the coil 17 and pointer 36 of the galvanometer and (2) the gap between the two arcuate clamp bars 71 and 72. Therefore, the pointer 122 indicates that position of the scale at which the pointer 122 will avoid being caught by either of the two arcuate clamp bars 71 and 72. When the pointer 36 occupies a position to the right, as viewed in Figs. 1 and 2, of the position indicated by the pointer 122, the pointer 36 will encounter the arcuate clamp bar 72 so as to cause an operation of the contacts associated with that clamp bar each time that the clamp bars are raised by the motor 55 acting through the crank 25 57, rocker 76 etc. Similarly, when the pointer 36 occupies a position to the left of the position indicated by the pointer 122 it will be caught by the clamp bar 71 so as to cause an operation of its contacts 74. 30

The pointers 36 and 122 must be so arranged as to avoid striking or interfering with each other. This will be discussed presently.

The pointer 36 of the galvanometer is capable of swinging through a limited angle of approximately 40°. For this reason, the graduated portion 121 and the windows 119 and 120 of the scale 39 are limited to the central portion thereof. These graduations and windows extend along the entire path or angular sweep of the pointer 36. 40 Each of the arcuate clamp bars 71 and 72 is sufficiently long that it alone can cover the complete range of movement of the pointer 36. Thus, the ring 81 may be rotated in a clockwise direction as viewed in Figure 4 so as to bring the 45 pointer 122 just beyond the extreme left deflectable position of the pointer 36. With the clamp bars in this condition, the pointer 36 will be caught by the clamp bar 72 each time that it is raised by the motor 55 regardless of the position 50 that the pointer 36 may occupy along its entire path of travel. Similarly, the clamping and contacting mechanism may be adjusted by rotating the ring 81 to bring the pointer 122 just beyond the extreme right deflectable position of the 55 pointer 36 so that the pointer 36 will be caught by the clamp bar 71 regardless of the position which the pointer may occupy. Obviously, the mechanism may be adjusted to bring the pointer 122 to any part of the graduated portion 121 of 60 the scale 39. With the pointer 122 set at some position along the graduated scale 121 intermediate the limits of the travel of the pointer 36, the bushing 38 of the pointer 36 will engage either the clamp bar 71 or the clamp bar 72 depending 65 upon whether the pointer 36 lies to the left or to the right of the pointer 122 at the time that the motor 55 raises the clamp bars.

The cover 105 is made sufficiently wide to permit this full scale adjustment of the clamping 70 bars, that is, to permit the pointer 122 and the gap between the clamping bars to be set at any position along the graduated scale. Thus, for example, when the pointer 122 is set at the left end of the graduated portion 121 of the scale, 75

and the clamp bar 71 lies entirely to the left of the left end thereof. The cover 105 extends beyond the graduated portion 121 of the scale to enclose the clamp bars in this position.

5 The pointer 122 and the blade or tip 38 of the pointer 36 must be so limited in size as to prevent them from interfering with each other. When these two pointers occupy the same position with respect to the graduated scale 118, that is, when 10 the pointer 122 is directly below the pointer 36, the bushing 38 of the pointer 36 is directly aligned with the gap between the two arcuate clamp bars 71 and 72. Therefore, when the clamp bars are raised by the motor 55, the pointer 36 will slip 15 into this gap so as to escape both clamp bars and it will not be lifted thereby. However, the pointer 122 which is carried by the clamp bar 72 will rise therewith. Inasmuch as the clamp bar 72 does not encounter the pointer 36, that clamp 20 bar will rise to approximately the position in which it touches the bar 73 and the pointer 122 will be carried to a higher position than it would have been carried had the clamp bar 72 caught the pointer 36. Therefore, the pointer 36 and its 25 tip 38 when in its normal unclamped position must entirely clear the pointer 122 when the latter is raised to its uppermost position by the motor 55.

In the construction shown in the drawings 30 wherein the stationary bar 73 is directly above the moving bars 71 and 72, the difference in the distance which the clamp bar 71, for example, rises when it encounters the bushing 37 on the pointer 36 and when it does not, can be no greater 35 than the thickness of the bushing 37. That is, the motion of the clamp bar 71 with respect to the ring 81 on which it is mounted and also with respect to the contacts on which it operates, is no greater than the thickness of the bushing 37. 40 Therefore, in the construction shown in the drawings, wherein the clamp bar operates the contacts directly, the spacing between the contacts 92 and 95, for example, must be less than the thickness of the bushing 37. Alternatively, the lower bars 45 71 and 72 may be offset with respect to the upper bar 73 so that when the bars do not engage the pointer, the rising bar is free to move past the stationary bar and rise considerably above it. This arrangement permits the motion executed 50 by the clamp bar in operating the contacts to exceed considerably the thickness of the pointer at the position in which it is clamped (for example at the bushing 37). However, offsetting the bars in this manner imposes a bending motion 55 upon the pointer which can be avoided only by employing an extra bar. Thus, the lower clamp bar may be arranged to rise between a pair of parallel stationary bars. However the clamping surfaces of the two parallel bars must be 60 finished with a high degree of precision in order to insure that the pointer engages them simultaneously. Therefore, where a motion equal to the thickness of a bushing (such as the bushing 37) which can be carried by the pointer is sufficient, it is preferred to have the two clamping bars aligned with each other as shown in the 65 drawings.

The relay of the present invention is not continuously responsive, in that it is not immediately responsive at all times to a change of current in its coil 17. This results from the fact that the position of the pointer is tested only intermittently by the clamping and contacting mechanism. It is incapable of responding reliably 70 to transient effects or other conditions

which have a duration less than the period of the periodic motion of the clamping mechanism. The instrument controls the operation of the contacts only in accordance with the position which the pointer occupies at the instant that it is caught by the clamping jaws. Thus, for example, if the clamp bars are in the clamping position, the current in the coil 17 may change suddenly by a considerable amount but the coil and pointer can not rotate in response thereto because 10 the pointer 36 will be held mechanically by the clamp bars. When the pointer subsequently is released, it will seek the position corresponding to the new value of current in the coil and when the clamping jaws subsequently are brought together again the relay will respond to the new value of current in the coil. However, if the current in the coil should return to its previous value, and the coil and pointer should respond thereto before the clamping jaws again grip the 15 pointer, the relay never will have responded to that particular current condition because the condition will not have persisted for a long enough period of time. In order to make the present instrument as rapid as possible in operation, it is desirable, under certain circumstances, to test the position of the pointer as frequently as possible. In order to permit the instrument accurately to indicate the value of current in its coil, the period during which the pointer is left 20 unclamped should exceed somewhat the time required by the pointer to move to a new position and come to rest. This time is approximately $\frac{1}{4}$ of the period of vibration of the instrument. It is further desirable to operate the clamping 25 mechanism as rapidly as possible so as to consume as little time as possible for the clamping or testing operation. However, the clamping bars should rise slowly enough to engage the pointer 30 35 40 45 50 55 60 65 70 75 80 85 90 95 100 105 110 115 120 125 130 135 140 145 150 155 160 165 170 175 180 185 190 195 200 Fig. 9) of the contacts 74 and 75 may be carried out of the cavity within the casting 105 where the contacts are located through openings 133 at the extreme sides and rear of the cover 105, 5 left uncovered by the plate 125.

Although the contacts 74 and 75 are shown and described as being of the normally open type, normally closed contacts or other more complex contact arrangements may be provided instead. 10 And while the relay of the present invention is shown and described as having two clamp bars, any number of clamp bars may be employed having equal or unequal lengths of arcs and with or without gaps between them. Where no 15 gap is provided between two clamp bars, it is possible that the two adjacent clamp bars may be operated simultaneously.

It is to be observed that the clamp bars 71 and 72 rise with a gradual motion and that the 20 cam 65 may be so arranged that the clamp bars also drop with a gradual motion. Under such conditions the time during which the contacts controlled by a clamp bar are closed or otherwise in an operated condition will depend upon the 25 motion which the clamping mechanism executes on the upstroke, after the contacts operate, and therefore upon the slack motion or motion which it executes before the contacts operate, the total motion as determined by the cam 65 being fixed. 30 It is desirable under certain conditions that the manner of operating the contacts should depend in part upon the position of the pointer along the clamp bar. By cutting the top of the clamp bar 71, for example, off at an angle, or by pivoting 35 the clamp bar at an angle as by tilting the pin 87, the clamp bar will be made to hold one portion of its clamping surface higher than another. If the pointer is caught by this high portion, the clamp bar will encounter the pointer sooner and disengage it later so as to hold its 40 contacts closed for a longer period of time than if the pointer is caught by a low portion of the bar. Thus, the two bars 71 and 72 may be arranged to be low near the gap between them so 45 that the length of time in which the contacts are closed increases with the deviation of the position of the pointer 36 from the position of the pointer 122. Thus, the apparatus which the 50 relay of the present controls may be arranged to effect a control function which varies in magnitude with the length of time that the contacts are closed so as to provide a graduated response which increases with the magnitude of the total 55 correction required. Alternatively, the bars 71 and 72 may be notched or stepped to provide a graduated response of the type indicated.

In the relay of the present invention a considerable advantage accrues from the fact that the clamp bars 71 and 72 are rotatable about the 60 same axis as the coil 17 and its pointer 36. This permits the clamp bars to be so arranged as always to engage the pointer at substantially the same portion thereof so that the comparatively heavy bushing 38 need not extend along more 65 than a very small part of the total length of the pointer 36. It also permits the upper or stationary bar 73 and lower bars 71 and 72 to be perfectly aligned in every position. If the upper and lower bars should be arranged so that they pass each 70 other in the manner already described, this alignment permits the upper and lower bars to pass each other with only a small space between them so as to limit the bending moment imposed upon the comparatively frail pointer of the galvanometer when clamping the same. It should

be apparent that the clamp bars could align themselves with an arc about the center of the coil for only one adjusted position of the clamp bars if the clamp bars rotated about any axis other than substantially the axis of the coil. 5

The fact that the rocker 76 carries the rotatable ring 81 rather than being rotatable itself also gives rise to certain advantages. Thus, the cam 65 and bell crank 57 are prevented from exerting any rotative effort upon the clamp bars 10 71 and 72 such as would tend to move the clamp bars to a new position along the scale 118. It also keeps the axis about which the clamp bars tilt fixed with respect to the path of travel of the bushing 38 and the limited angle of motion 15 of the pointer 36. Therefore, the axis about which the clamp bars rock can be given the most advantageous orientation with respect to the pointer 36 at every rotated position of the clamp bars. In the device shown and described in the 20 present application, the axis about which the clamp bars rock or tilt is given that orientation which produces the greatest rise of the clamp bars in the region in which the pointer moves for a 25 given angle of tilt. With this arrangement, the ring 81 which carries the clamp bars can be rotated through any angle, even 360°, without diminishing the motion which the clamp bars execute in the region occupied by the pointer. This 30 arrangement further permits the use of a simple mechanism for automatically disengaging the drive for adjusting the position of the clamp bars during the time that the clamp bars are raised to bring them into a clamping attitude with respect to the pointer 36. 35

The fact that the gear teeth on the ring 81 face upward permits them to disengage and swing clear of the teeth of the worm 14 when the clamping mechanism is tilted; and it permits these gear teeth to serve as a stop for the tilting and 40 clamping mechanism when that mechanism drops to its lowermost position. By employing the worm 14, through its engagement with the teeth of the ring 81, as the stop for the rocker 76 and the apparatus carried thereon, these teeth are brought 45 firmly into engagement so as to eliminate any back lash or play between the teeth of the worm 14 and those of the ring 81.

The apparatus of the present invention may be employed, for example, in a temperature regulating system, the temperature of the apparatus to be controlled may be measured by a resistance thermometer, thermocouple or other known electrical device, the galvanometer coil 17 of the present invention being employed therewith as the 50 indicator or current measuring device. The pointer 122 may be adjusted to that position of the scale which corresponds to the temperature at which it is desired to maintain the controlled apparatus. The contacts of the clamp bars 71 55 and 72 may be arranged respectively to heat and cool that apparatus, or the cooling function for example may be omitted in which case only the contacts 74 of the clamp bar 71 will control a load. As long as the pointer 36 occupies the same 60 scale position as the pointer 122, neither of the clamp bars 122 will operate its contacts. When the pointer 36 moves slightly to the left of the 65 position indicated by the pointer 122, it will be caught by the clamp bar 71 and thereby will cause the heating apparatus to be set into operation each time that the clamp bars are raised by the motor 55. This will increase the temperature of the device being controlled so that the electrical 70 temperature measuring apparatus connected 75

to the coil 17 eventually will cause the pointer 36 to deflect towards the right. However, the pointer 36 will continue to cause the contacts which are associated with the arcuate clamp bar 5 71 periodically to be operated until the temperature rises to such value that the pointer 36 moves to the position indicated by the pointer 122 or to the right thereof.

It will be apparent to those skilled in the art 10 that the specific embodiment of the invention herein shown and described is illustrative only, and that the invention is capable of numerous modifications and variations. Therefore, the invention should not be limited except by the scope 15 of the appended claims.

We claim:

1. In combination in a device of the class described, a galvanometer having a pointer which is rotatable about an axis, a pair of clamp bars 20 adapted to clamp said pointer and means for repeatedly moving at least one of said bars to bring said bars into a clamping attitude with respect to said pointer and to withdraw them therefrom, electric contact mechanism adapted to be operated by mechanical force, at least one of said 25 clamp bars being mechanically coupled to said contact mechanism so that the force with which said bars clamp said pointer serves to operate said switch. 30

2. In combination in a device of the class described, a galvanometer having a pointer which is rotatable about an axis, a pair of clamp bars adapted to clamp said pointer in rotated position, said clamp bars being arcuate and having the centers of their arcs substantially at said axis 35 of said pointer and means for repeatedly moving at least one of said bars to bring said bars into a clamping attitude with respect to said pointer and to withdraw them therefrom, at least one of said 40 bars being rotatable substantially about said axis of the galvanometer and extending less than 360° about said axis.

3. In combination in a device of the class described, a galvanometer having a pointer which is 45 rotatable about an axis, said pointer consisting of a thin-wall metal tube, a pair of clamp bars adapted to clamp said pointer, said clamp bars being arcuate and having the centers of their arcs substantially at said axis of the galvanometer, means for repeatedly moving at least one 50 of said bars to bring said bars into a clamping attitude with respect to said pointer and to withdraw them therefrom, at least one of said bars being rotatable substantially about said axis of the galvanometer and extending less than 360° 55 about said axis, and a bushing on said pointer for supporting the pressure exerted on said pointer by the clamping action of said clamp bars, said bushing being carried by said pointer on the portion thereof which encounters said clamp bars. 60

4. In combination in a device of the class described, a galvanometer having a pointer which is rotatable about an axis, a graduated scale with respect to which said pointer indicates its own 65 deflected position, a pair of clamp bars having clamping surfaces adapted to clamp said pointer, means for moving at least one of said bars to bring said clamp bars into a clamping attitude with respect to said pointer and to withdraw them therefrom, at least one of said bars being rotatable substantially about the axis of said pointer and having its clamping surface limited in the direction about said axis, a second pointer rotatable substantially about said axis with the rotatable 70 clamp bar, said second pointer indicating on said 75

graduated scale the position of the margin of the limited clamping portion of said rotatable clamp bar, said means including an electric contact mechanism adapted to be operated by mechanical force and so coupled to one of said clamp bars that the force with which said bars clamp said pointer serves to operate said switch. 5

5. In combination in a device of the class described, a galvanometer having a movable pointer, a pair of clamp bars having clamping surfaces 10 adapted to clamp said pointer, means for repeatedly moving at least one of said bars to bring said clamp bars into a clamping attitude with respect to said pointer and to withdraw them therefrom, at least one of said clamp bars having 15 its clamping surface so limited in extent as to cover less than the full path of motion of said pointer whereby said clamp bars are adapted to clamp said pointer only when said pointer occupies certain portions of its path of motion, electric contact mechanism adapted to be operated by mechanical force, at least one of said clamp bars being mechanically coupled to said contact mechanism so that the force with which said bars clamp said pointer serves to operate said switch. 25

6. In combination in a device of the class described, a galvanometer having a pointer which is rotatable about an axis through a limited angle, a pair of clamp bars for clamping said pointer, and means for moving at least one of said clamp bars so as to bring said clamp bars into a clamping attitude, said means comprising a support for said one clamp bar, said support being tiltable about a fixed axis which is substantially perpendicular to said axis of the galvanometer and which is substantially perpendicular to the median position of said pointer in said limited angle of rotation. 30

7. In combination in a device of the class described, a galvanometer having a coil carried on 40 taut suspensions and having a pointer carried on said coil, said coil and pointer being rotatable through a limited angle, said pointer extending from said coil and having a clamp engaging portion removed from the axis of the taut wire suspensions in a radial direction and removed in a direction along said axis of the taut wire suspensions from the center of said coil, a pair of clamp bars for clamping said pointer, one of said clamp bars being movable about a tilting axis to bring 50 said clamp bars into a clamping attitude, said tilting axis being substantially perpendicular to said axis of the taut wire suspensions and substantially perpendicular to a line radiating from the axis of the taut wire suspensions and intersecting the median position in the range of positions of the clamp engaging portion of said pointer, said range of positions of said clamp engaging portion being determined by said limited angle of rotation of said pointer, said tilting axis 55 being located with reference to the direction of said axis of the taut suspension wires between said clamp engaging portion of said pointer and the center of said coil, said tilting axis being located with respect to the direction of said line radiating from the axis of the taut wire suspensions and intersecting said median position of said clamp engaging portion of said pointer, to that side of said clamp engaging portion of the pointer on which lies said axis of the taut wire 60 suspensions. 65

8. In combination in a device of the class described, a galvanometer having a pointer which is rotatable about an axis through a limited angle, a pair of clamp bars adapted to clamp 70 75

said pointer; at least one of said clamp bars being movable about a fixed tilting axis to bring said clamp bars into a clamping attitude, said fixed tilting axis being substantially perpendicular to the axis of rotation of the pointer and substantially perpendicular to the median position of said pointer in the limited angle of rotation thereof, at least one of said clamp bars being rotatable approximately about the axis of rotation of said pointer and extending about said axis less than 360°.

9. In combination in a device of the class described, a galvanometer comprising a substantially closed housing, a coil therein and a pointer carried by said coil, said coil and pointer being rotatable about a coil axis through a limited angle, a pair of clamp bars adapted to clamp said pointer, means for moving at least one of said clamp bars so as to bring said clamp bars into a clamping attitude with respect to said pointer, said means comprising a supporting structure for said one clamp bar, said supporting structure comprising a rocker supported on said housing and tiltable thereon about an axis which is substantially perpendicular to the coil axis and substantially perpendicular to a median position of said pointer with respect to said limited angle, said supporting structure comprising also a member rotatable on said rocker about an axis which is substantially coincident with said coil axis for one tilted position of said rocker, said one clamp bar extending about said axis less than 360°.

10. In combination in a device of the class described, a galvanometer having a pointer which is movable along a path of travel thereof, a pair of clamp bars adapted to clamp said pointer, first means for moving at least one of said clamp bars to bring said clamp bars into a clamping attitude with respect to said pointer and to withdraw them therefrom, at least one of said clamp bars being movable along said path of travel of the pointer and being adapted to extend less than the full length of said path of travel in at least one position of said clamp bar along said path of travel, and second means for driving said last mentioned one clamp bar along said path of travel, said second means being operable only when said first means has withdrawn said clamp bars from a clamping attitude with respect to said pointer.

11. In combination in a device of the class described, a galvanometer housing, a coil supported therein and rotatable therein about a coil axis through a limited angle, a pointer carried on said coil and rotatable therewith, said pointer extending out of said housing, a pair of clamp bars adapted to clamp said pointer, means for supporting one of said clamp bars, said means comprising a ring shaped rocker encircling said housing and supported thereon, said rocker being tiltable on said housing about a rocker axis which is fixed with respect to said housing, said means comprising also a ring shaped rotatable member encircling said housing carried on said rocker and rotatable on said rocker about a third axis which is fixed with respect to said rocker, said one clamp bar being carried by said rotatable member and being rotatable therewith, said one clamp bar extending less than 360° about said coil axis and about said third axis and being adapted to engage said pointer at a point off said coil axis, off said rocker axis and off said third axis, whereby (1) said one clamp bar is adapted to tilt with said rocker into and out of a clamping attitude with respect to said pointer;

(2) said clamp bar when in said clamping attitude is adapted to engage and clamp said pointer or to avoid clamping the same in accordance with the rotated position of said pointer relative to the rotated position of said one clamp bar; and (3) said clamp bar is adapted to rotate to change its rotated position, so as to change the respective rotated positions at which said pointer is adapted to escape and engage said clamp bar.

12. In combination in a device of the class described, a galvanometer comprising a substantially closed housing, a coil therein, and a pointer carried by said coil, said pointer and coil being rotatable together about a coil axis through a limited angle, a pair of clamp bars adapted to clamp said pointer, means for moving at least one of said clamp bars into a clamping attitude with respect to said pointer and to withdraw them therefrom, said means comprising a supporting structure for said one clamp bar, said supporting structure comprising a rocker supported on said housing and tiltable thereon about a rocker axis, said rocker axis being fixed with respect to said housing, said supporting structure comprising also a member carried on said rocker and rotatable about a third axis, said third axis being fixed with respect to said rocker and lying approximately in the direction and position of said coil axis of the galvanometer, said one clamp bar being rotatable with said rotatable member and extending about said coil and third axes less than 360°, a driving member for said rotatable member adapted to make driving engagement with said rotatable member at a position off said third axis about which said rotatable member rotates on said rocker and off said rocker axis about which said rocker tilts, said rocker being adapted to tilt about said rocker axis to accomplish the following in a single motion in one direction of rotation about said rocker axis: (1) move said one clamp bar to bring said clamp bars into a clamping attitude with respect to said pointer; and (2) withdraw said rotatable member from driving engagement with said driving member.

13. In combination in a device of the class described, a galvanometer comprising a substantially closed housing, a coil therein and a pointer carried on said coil, said coil and pointer being rotatable together about a coil axis through a limited angle, the median position of said pointer in said angle being forward of said housing, a pair of clamp bars lying above and below the path of said pointer for clamping said pointer, means for moving the lower one of said clamp bars so as to bring said clamp bars into a clamping attitude with respect to said pointer, said means comprising a supporting structure for said lower clamp bar, said supporting structure comprising a rocker encircling said housing and having a circular seat encircling said housing, said rocker being supported on said housing and tiltable thereon about a rocker axis which is fixed with respect to said housing, said rocker axis lying substantially perpendicular to said coil axis and substantially perpendicular to said median position of said pointer in said limited angle, said supporting structure comprising also a rotatable member encircling said housing, said rotatable member being carried on said rocker and being rotatable on said seat about a third axis which is fixed with respect to said rocker and which is substantially coincident with said coil axis for one tilted position of said rocker, said lower clamp bar extending about said coil axis and about

- said third axis less than 360°, said rotatable member having teeth arranged in a circular pattern thereon about said third axis, a worm engaging said teeth at the rear of said circular pattern, 5 said worm being rotatable about an axis which is fixed with respect to said housing for rotating said rotatable member on said rocker, said axis of said worm lying approximately parallel to said rocker axis, said rocker axis lying forward of said axis of said worm and aft of said lower clamp bar, said teeth of said rotatable member being adapted to disengage said worm by dropping away therefrom, said rotatable member being adapted to tilt with said rocker about said rocker axis 10 to accomplish the following in a single motion in one direction of rotation about said rocker axis: (1) raise said lower clamp bar into a clamping attitude with respect to said pointer; and (2) drop said teeth of said rotatable member out 15 of engagement with said worm.
14. In combination in a device of the class described, a galvanometer comprising a substantially closed housing, a coil therein, and a pointer carried by said coil, said pointer and coil being 20 rotatable together about a coil axis through a limited angle, a pair of clamp bars for clamping said pointer, means for moving at least one of said clamp bars so as to bring said clamp bars into a clamping attitude with respect to said 25 pointer and to withdraw them therefrom, said means comprising a supporting structure for said one clamp bar, said supporting structure comprising a rocker supported on said housing and tiltable thereon about a rocker axis, said 30 rocker axis being fixed with respect to said housing, said supporting structure comprising also a member carried on said rocker and rotatable about a third axis, said third axis being fixed with respect to said rocker and lying approximately 35 in the direction and position of said coil axis, said one clamp bar being rotatable with said rotatable member and extending about said coil and third axes less than 360°, a driving member for 40 said rotatable member adapted to make driving engagement with said rotatable member at a position off said third axis about which said rotatable member rotates on said rocker and off said rocker axis about which said rocker tilts, said rocker being adapted to tilt about said rocker 45 axis to accomplish the following in a single motion in one direction of rotation about said rocker axis: (1) move said one clamp bar to bring said clamp bars into a clamping attitude with respect to said pointer; and (2) withdraw said 50 rotatable member from driving engagement with said driving member, a graduated scale cooperating with said pointer for indicating on said scale the rotated position of said pointer about said coil axis, a second pointer rotatable with 55 said rotatable member for indicating on said scale the rotated position of said one clamp bar about said third axis, 60 said rotatable member for indicating on said scale the rotated position of said one clamp bar about said third axis.
15. In combination in a device of the class described, a galvanometer comprising a substantially closed housing, a coil therein and a pointer carried on said coil, said coil and pointer being rotatable together about a coil axis through a limited angle, the median position of said pointer in said angle being forward of said housing, a 65 pair of clamp bars lying above and below the path of said pointer for clamping said pointer, means for moving the lower one of said clamp bars so as to bring said clamp bars into a clamping attitude with respect to said pointer, said 70 means comprising a supporting structure for said lower clamp bar, said supporting structure comprising a rocker encircling said housing and having a circular seat encircling said housing, said rocker being supported on said housing and tiltable thereon about a rocker axis which is fixed with respect to said housing, said rocker axis lying substantially perpendicular to said coil axis and substantially perpendicular to said median position of said pointer in said limited angle, said supporting structure comprising also a rotatable member encircling said housing, said rotatable member being carried on said rocker and being rotatable on said seat about a third axis which is fixed with respect to said rocker and which is substantially coincident with said coil 75 axis for one tilted position of said rocker, said lower clamp extending about said coil axis and about said third axis less than 360°, said rotatable member having teeth arranged in a circular pattern thereon about said third axis, a worm engaging said teeth at the rear of said circular pattern, said worm being rotatable about an axis which is fixed with respect to said housing for rotating said rotatable member on said rocker, said axis of said worm lying approximately parallel to said rocker axis, said rocker axis lying forward of said axis of said worm and aft of said lower clamp bar, said teeth of said rotatable member being adapted to disengage said worm by dropping away therefrom, said rotatable member being adapted to tilt with said rocker about said rocker axis to accomplish the following in a single motion in one direction of rotation about said rocker axis: (1) raise said lower clamp bar into a clamping attitude with respect to said 80 pointer; and (2) drop said teeth of said rotatable member out of engagement with said worm, a graduated scale cooperating with said pointer for indicating on said scale the rotated position of said pointer about said coil axis, a second pointer rotatable with said rotatable member for indicating on said scale the rotated position of said one clamp bar about said third axis, said lower clamp bar being hinged on said rotatable member about an axis which is approximately perpendicular to said third axis, and contacts carried by said rotatable member and adapted to be operated by said lower clamp bar when said clamp bars engage and clamp said pointer.
16. In a device of the class described, a frame having a cylindrical portion, a galvanometer housed in said cylindrical portion of said frame, a rocker carried by said cylindrical portion, a ring positioned on said rocker and carried thereby, said ring encircling said cylindrical portion, a pair of clamp bars pivotally supported on said ring, a stationary clamp bar carried on said frame and positioned near each of said pivoted clamp bars, means carried on said frame for imparting a rocking movement to said rocker and for thereby rocking said pivoted clamp bars towards and away from said stationary clamp bar, a pointer actuated by said galvanometer and adapted to swing between said stationary clamp bar and said pivoted clamp bars, electrical contacts carried by said ring and adapted to be operated by said pivoted clamp bars, said ring, contact and pivoted clamp bars being rotatable together on said rocker, and a housing enclosing the foregoing apparatus.
17. In combination in a device of the class described, a galvanometer having a pointer which is rotatable about an axis, a pair of clamp bars adapted to clamp said pointer and means for moving one of said bars so as to bring said bars

into a clamping attitude with respect to said pointer, said means including a power actuator and a driving connection between said power actuator and said one bar, and electric contact mechanism included in said driving connection adapted to be operated by the pressure with which said bars clamp said pointer.

18. The combination of the immediately preceding claim wherein said means includes a tilt-
10 able member carrying said contact mechanism, wherein said contact mechanism includes a movable part for urging said one clamp bar into its clamping attitude, and wherein said power actuator tilts said tilttable member to move said contact mechanism against said bar, whereby when the pointer obstructs the motion of said bar, the power actuator operates said switch mechanism.

19. In combination in a device of the class 20 described, a galvanometer having a pointer rotatable about an axis, a pair of clamp bars adapted to clamp said pointer, means for moving one of said bars toward said pointer to bring said bars into a clamping attitude and electric contacts operated by said means when said bars clamp said pointer, said means including a tilt-
25 able member and a power actuator for tilting it, said contacts comprising a pair of cantilever contact blades supported on said tilttable member, one of said blades being flexible and bearing against said one contact bar to urge it toward clamping position as said tilttable member tilts so that when the pointer obstructs the motion of said bar said one blade must flex as said tilt-
30 able member tilts, whereby to operate said contacts.

20. In combination in a device of the class 40 described, a galvanometer having a pointer which is rotatable about an axis, said pointer consisting of a thin-wall tube, a pair of clamp bars adapted to clamp said pointer, means for moving at least one of said bars to bring said bars into a clamping attitude with respect to said pointer, and a bushing on said pointer for supporting the pressure exerted on said pointer by
45 the clamping action of said clamp bars, said

bushing being carried by said pointer on the portion thereof which encounters said clamp bars.

21. In combination in a device of the class de-
5 scribed, a galvanometer having a pointer which is movable along a path of travel thereof, a pair of clamp bars adapted to clamp said pointer, means for moving at least one of said clamp bars to bring said clamp bars into a clamping attitude with respect to said pointer and to withdraw them therefrom, at least one of said clamp bars being movable along said path of travel of the pointer and being adapted to extend less than the full length of said path of travel in at least one position of said clamp bar along said 10 path of travel, and adjusting means for driving said last mentioned one clamp bar along said path of travel, said last means being operable only when said clamp bars are not in a clamping attitude with respect to said pointer, said ad-
15 justing means being incapable of operating said clamp bars into or out of a clamping attitude with respect to said pointer.

22. In combination in a device of the class de-
25 scribed, a galvanometer having a pointer rotat-
able about an axis, means for detecting the position of said pointer, said means including a clamp bar adapted to be moved toward said pointer to bring it into a clamping attitude with respect thereto, a tilttable member having a pro-
30 jection thereon for supporting a contact structure, a sheet of insulating material folded over said projection to cover the extended end and two opposed faces of said projection, the ends of said sheet extending out away from said op-
35 posed faces of said projection, and contact blades mounted cantilever fashion on said pro-
jection on the outside of said sheet of insulat-
ing material, said sheet being wider than either said projection or said contact blades, said tilt-
40 able member being adapted to rock said contacts against said clamp bar to urge said bar toward said pointer.
